[57] CLAIM

The ornamental design for a vise jaw, as shown and described.

DESCRIPTION

FIG. 1 is a front plan view of a vise jaw according to the present invention, the rear surface of the vise jaw being a mirror image thereof;

FIG. 2 is a right side elevational view of FIG. 1 illustrating the teeth of the present invention, the left side being a mirror image thereof;

FIG. 3 is a bottom side elevational view of FIG. 1, the top being a mirror image thereof;

FIG. 4 is a plan view of an alternate embodiment of a vise jaw according to the present invention;

FIG. 5 is a rear plan view of the vise jaw of FIG. 4;

FIG. 6 is a left side elevational view of FIG. 4 illustrating the teeth of the vise jaw;

FIG. 7 is a right side elevational view of FIG. 4 illustrating the rubber friction pad of the vise jaw;

FIG. 8 is a top end view of FIG. 4, the bottom end view being a mirror image thereof;

FIG. 9 is a plan view of a second alternate embodiment of a vise jaw according to the present invention, the rear surface of the vise jaw being a mirror image thereof;

FIG. 10 is a right side elevational view of FIG. 9 illustrating the teeth of the vise jaw, the left side being a mirror image thereof; and,

FIG. 11 is a top end view of FIG. 9, the bottom being a mirror image thereof.
